REFRIGERATOR EVAPORATOR

Roland H. Money, Cincinnati, Ohio, assignor to
The Crosley Radio Corporation, Cincinnati,
Ohio, a corporation of Ohio

Application September 23, 1935, Serial No. 41,643

8 Claims. (Cl. 62—126)

5 My invention relates to evaporators for refrigerators in which provision is made for one or more ice forming trays. It is applied more particularly to the type of evaporator in which the refrigerant conducting passages in the evaporator are formed by corrugations or ribs in the outer sheet or sheets of the structure, as distinguished from the passages being formed of tubes or a coil of tubes.

10 In the type of evaporator with which I am concerned, formed of sheet metal with the passages running in parallel lines along the sides thereof, it has been considered impractical to supply refrigerant to the shelf or shelves within the evaporator structure on which the ice trays are supported, except by introducing it directly to the shelf before conducting it to the rest of the evaporator. The reason for this is that the mere provision of ducts leading into the shelf, from the main ducts of the evaporator, as by forming the 15 shelf of two pieces secured at the edges with one of them corrugated to form the passages or ducts, will not suffice. In such a case there will be no flow of refrigerant in the ducts, and indeed oil will collect therein, which excludes refrigerant.

20 It is my object to provide for a refrigerated ice tray shelf across the interior of the evaporator. In this connection I provide for positive assurance of flow of refrigerant and by the construction avoid any pockets for oil to collect and 25 block the refrigeration of the shelf.

That such a shelf is highly useful in quickly forming ice in an ice tray or freezing other materials as desired, is obvious.

30 I have illustrated in the appended drawings a preferred form of evaporator structure embodying my invention, selecting for purposes of illustration the type of evaporator which is built along the same lines as that described in my 35 United States Letters Patent No. 1,975,659, dated October 2, 1934. In the claims which are added to this specification, I will set forth the novelty inherent in the structure described, irrespective of those individual features thereof with which 40 my present invention is not concerned, but which are shown and described in order to specify a complete and fully operative structure.

In the drawings:

Fig. 1 is a front elevation of my improved 45 evaporator.

Fig. 2 is a side elevation of Fig. 1.

Fig. 3 is a section along the line 3—3 of Fig. 2.

Fig. 4 is a side elevation of a modified form of evaporator.

55 Fig. 5 is an end elevation partly in section,

taken through the last figure showing the internal arrangement.

The outer sheet of the evaporator structure shown, is indicated at 1, and extends from the two lower edges of the structure, up the sides and across the top thereof, being bent to form part of a header as at 2. This sheet is formed with ribs therein for refrigerant conductors as will be described.

Welded to this outer sheet at the edges and 10 preferably at points intermediate the ribs of the outer sheet is an inner structure. The upper portion thereof is formed of a sheet 3 which is formed into a closed shape to fit within the upper portion of the formed outer sheet, with a 15 depression at the top as at 4 to complete the header of the structure. This sheet 3, forms the shelf 5 on which, in the example shown, two ice trays can be mounted.

A sheet 6, is also formed into a closed shape 20 to fit the lower portion of the outer bent sheet and the shelf 5. This sheet has ribs at the top to form the refrigerant passageways for the tray shelf as will be described, and at its edges is welded to the said tray shelf as well as to the 25 side sheet.

The sheet 6 when installed does not come to the bottom of the device, i. e. the sides extend beyond it. The bottom of the evaporator is formed of a sheet 7, which is formed with ridges, as will 30 be described, matching and communicating with the ridges of the outer sheet. This bottom 7 has a rounded depression at 8, matching a rounded projection 9 in the bottom of the sheet 6, thereby forming the bottom header of the device. 35 The bottom sheet is flanged at 10, which flange is the portion that is welded to the side sheet at its lower ends as well as the short projecting distance of its lower edges.

The side sheet and bottom sheets are those 40 shown in my patent above referred to. The manner of putting the device together is also described in my said Letters Patent with the exception that the interior of the structure is formed of two closed sheet bodies instead of one, this 45 latter structure having been adopted to provide for the refrigerated shelf.

Referring now to the ridges which form the refrigerant ducts of the evaporator, the ridges 11 and 12 in the outer sheet communicate with 50 the central rounded portion 2 that forms the header. Every other one of these ridges i. e. the ridges 11, terminates where the refrigerated shelf is located. The intervening ridges continue down to the lower end at each side of the 55

outer shell, but in a double size or thereabouts, so as to form larger ducts or ridges 13, than the upper portions thereof, indicated at 12.

The ridges 14 in the base sheet communicate with the ridges 13, and in number are the same as the ridges 13, as well as in size.

The upper portion of the lower section 6 of the evaporator which underlies the shelf 5, is formed with ridges therein which are in the form of loops 15. These loops are arranged so that one leg of each loop comes opposite the upper end of a ridge 13, and the other leg comes opposite the terminus of a ridge 11.

As so constructed refrigerant flows out from the bottom header through the ducts formed by the ridges in the base and rises through the ducts formed by the ridges 13. A larger quantity can flow in these ducts than would flow if they were smaller in dimensions. Where the shelf ducts or loops 15 communicate with the upper ends of the duct portions 13, some of the refrigerant which cannot pass up to the upper header through the narrow duct portions 12, will pass around through the loops and from the ends of the loops will flow through the ducts 11 to the upper header.

It will be noted that flow is required through the shelf ducts by the structure described, and that there will be no pockets in which oil can collect and block the action of the evaporator. At the same time there is no part of the evaporator which is not refrigerated at the sides. Merely larger ducts take the place of some of the ducts which normally would extend down the sides.

I have shown a shelf 16 across the lower half of the evaporator interior, but this is not necessary. I have shown tray stops 17 in the several shelves including the refrigerated shelf. These are humps pressed up in the sheets forming the shelves or shelf tops as the case may be.

It will be apparent that the structure now described with modifications necessary and obvious to accommodate other structures of the type of evaporator now described, could be readily applied to any of such evaporators. The number of sheet parts of which the evaporator is built could, for example, be increased. The shape of the entire structure could be changed, and the number and size of shelf ducts and arrangements therefor cut down. The device could be one tray wide or two or three trays wide. With an increase in number of ducts more shelves could be refrigerated. In such an arrangement staggered ducts in the main walls could readily be arranged to bring the shelf loops in series with the main flow.

The modification shown in Figs. 4 and 5, shows a structure according to my invention, whereby a series of shelves are provided for. The outer shell of the evaporator is formed with ducts 30, as a lower set connecting with the bottom header and ducts, ducts 31, offset from the ducts 30, and ducts 32 offset from the ducts 31 and connecting to the top header. The shelves in this modification are like those in the other form. The loop ducts 33 in the lower shelf connect ducts 30 with ducts 31, and the loop ducts 34 in the upper shelf connect ducts 31 with ducts 32.

In this form also, there is a flow of refrigerant through the shelves, accomplished by an interruption of ducts.

By stating the above possible modifications, I do not wish to exclude others, nor to minimize the advantages of the particular arrangement

shown, which I consider to be advantageous because of its simplicity and inexpensiveness.

Having thus described my invention, what I claim as new and desire to secure by Letters Patent is:—

1. In an evaporator of the sheet type ribbed to form ducts, a shelf formed transverse the structure, a ribbed sheet secured to said shelf to form refrigerant passages between them, said passages formed as loops, and the ribs constituting the ducts in the outer sheet of the structure being formed to cause refrigerant flowing up through them to pass through and out of said loops.

2. An evaporator comprising a lower header, and upper header, a sheet metal case formed of ribbed outer walls to form ducts from the lower header to the upper header, a shelf intermediate of and across the said sheet metal case for an ice tray or the like, said shelf being formed of two pieces of sheet metal ribbed to form ducts in the form of loops, and so mounted as to cause these ducts to communicate with the ducts in the case, the said ducts in the case being formed to enforce flow of refrigerant through the said loops.

3. An evaporator comprising a lower header, and upper header, a sheet metal case formed of ribbed outer walls to form ducts from the lower header to the upper header, a shelf intermediate of and across the said sheet metal case for an ice tray or the like, said shelf being formed of two pieces of sheet metal ribbed to form ducts in the form of loops, and so mounted as to cause these ducts to communicate with the ducts in the case, the ducts in the case being arranged so that one end of each loop communicates with a duct extending only from the loop to the upper header, and so that the other end of each loop communicates with a duct in the case which extends from the lower header to the upper header.

4. An evaporator comprising a lower header, and upper header, a sheet metal case formed of ribbed outer walls to form ducts from the lower header to the upper header, a shelf intermediate of and across the said sheet metal case for an ice tray or the like, said shelf being formed of two pieces of sheet metal ribbed to form ducts in the form of loops, and so mounted as to cause these ducts to communicate with the ducts in the case, the ducts in the case being arranged so that one end of each loop communicates with a duct extending only from the loop to the upper header, and so that the other end of each loop communicates with a duct in the case which extends from the lower header to the upper header, said latter duct being of greater capacity from the lower header to said point of communication, than from the point of communication to the upper header.

5. An evaporator comprising an outer sheet metal piece ribbed to form ducts extending up the sides thereof, an inner sheet metal piece arranged to nest within and be welded to the outer piece, thereby forming part of an evaporator, a sheet metal piece to nest within the outer sheet below the piece last above noted, forming the remainder of the inner sides of the evaporator, said latter piece ribbed to form ducts extending between its upper part and the lower part of the first mentioned inner piece, which ducts communicate with ducts formed in the outer sheet, and means located below the latter piece and secured to the ends of the outer piece to form the bottom of the evaporator.

6. An evaporator comprising an outer sheet metal piece ribbed to form ducts extending up the sides thereof, an inner sheet metal piece arranged to nest within and be welded to the outer piece, thereby forming part of an evaporator, a sheet metal piece to nest within the outer sheet below the piece last above noted, forming the remainder of the inner sides of the evaporator, said latter piece ribbed to form ducts extending between its upper part and the lower part of the first mentioned inner piece, which ducts communicate with ducts formed in the outer sheet, and means located below the latter piece and secured to the ends of the outer piece to form the bottom of the evaporator, the ducts in said latter piece being in the form of loops communicating with alternate ducts in the outer casing.
7. An evaporator comprising an outer sheet metal piece ribbed to form ducts extending up the sides thereof, an inner sheet metal piece arranged to nest within and be welded to the outer piece, thereby forming part of an evaporator, a sheet metal piece to nest within the outer sheet below the piece last above noted, forming the remainder of the inner sides of the evaporator, said latter piece ribbed to form ducts extending

between its upper part and the lower part of the first mentioned inner piece, which ducts communicate with ducts formed in the outer sheet, and means located below the latter piece and secured to the ends of the outer piece to form the bottom of the evaporator, the ducts in said latter piece being in the form of loops communicating with alternate ducts in the outer casing, said ducts in the outer casing being of greater capacity below than above the entrance to the said loops, and from the exit of said loops extending only upwardly therefrom.

8. A sheet metal evaporator having ducts, wherein said ducts are formed by the corrugating of metal walls secured together at their edges, said evaporator having ducts formed in the side walls thereof, shelves across the interior of the evaporator, and loop ducts in the shelves extending from a point of communication with a duct in one of the side walls, to a point of communication with another duct in the same side wall, said latter duct terminating at said point of communication, whereby refrigerant is caused to flow through said shelf ducts.
